J. C. DARST,
SAFETY POCKET.
APPLICATION FILED NOV. 1, 1918.

1,321,289.

Patented Nov. 11, 1919.

UNITED STATES PATENT OFFICE.

JAMES C. DARST, OF PORTSMOUTH, VIRGINIA.

SAFETY-POCKET.

1,321,289.

Specification of Letters Patent. Patented Nov. 11, 1919.

Application filed November 1, 1918. Serial No. 260,640.

To all whom it may concern:

Be it known that I, JAMES C. DARST, a citizen of the United States, at present residing at Portsmouth, in the county of Norfolk and State of Virginia, have invented a new and Improved Safety-Pocket, of which the following is a specification.

My invention generally relates to pockets, pouches and the like, for personal wear and especially designed for securely retaining valuables contained therein against nefarious attempt on the part of pick pockets and others to remove them without attracting the attention of the wearer to such attempt. Primarily, my invention seeks to provide a very simple and inexpensive safety pocket or pouch for holding bills of currency upon the inner side of a trousers waistband and which has peculiarly arranged closure means along the mouth or open edge thereof, which effectively provides against the removal of the contents of the said pocket or pouch by others without notice to the wearer and which may be quickly adjusted by the wearer, whereby single ones of the package of bills contained in the pocket may be removed without disturbing the other bills, without unbuttoning the vest or other garment and without detection.

Another object of my invention is to provide a peculiarly constructed fabric pocket or pouch, which fabric may be light leather, chamois skin or kid, that may be readily applied for use as a substitute for a money belt, when finishing up trousers waistband or easily applied by any one to the waistband of worn trousers.

A further object of my invention is to provide a pocket or pouch of the character stated formed of a single piece of fabric shaped up to snugly receive a package of bills in their flatwise extended condition, that can be attached lengthwise along that portion of the waistband of trousers having a pair of inwardly projected attached suspender buttons, the open or mouth end of the pocket or pouch having button holes for connecting with the suspender buttons, the said buttons and the straps that connect therewith forming means for positively holding the mouth of the pocket closed against free access to the contents of the pocket or lifting the package of bills out of the said pocket without disconnecting either one of the said suspender strap and button connections.

With the above and other objects in view and other objects hereinafter mentioned, my invention is a safety pocket that embodies the peculiar features of construction that will be first explained in detail, then specifically pointed out in the appended claims and illustrated in the accompanying drawings, in which:

Figure 1 is a perspective view of my safety pocket device operatively applied to the inside waistband of a pair of trousers, the same being illustrated as in a safety suspender locked position.

Fig. 2 is a similar view and illustrates the mouth of the pocket or pouch so opened as to permit of withdrawal of one of the package of bills contained therein.

Fig. 3 is a detail cross section on the line 3—3 on Fig. 1.

Fig. 4 is a detail perspective view of a modified construction of my invention.

Fig. 5 is a cross section thereof.

In carrying out my invention, I provide a flexible pocket or pouch formed up from a single piece of fabric by folding the said fabric lengthwise upon itself and connecting the opposite ends, by sewing a hem along the meeting edges 2, to thereby produce an elongated pouch 1 open along the entire upper edge, and to add strength and finish to the said upper open edge, the opposite members that constitute the said upper edge are hemmed as indicated by 3—3.

A practical application of my improved safety pocket or pouch is illustrated in Figs. 1 and 2, by reference to which it will be seen that the pocket is of such length and depth that it permits of slipping a package of bills of currency, in flatwise condition, therein, so that the opposite ends of the said package have practically no endwise play in the pocket and the upper edge of the package is in a plane sufficiently below the top edge or mouth of the pocket to provide a closure portion 4 to which the devices that close the mouth are attached.

When arranged as in Figs. 1 and 2, the closure devices comprise the pair of suspender buttons 5—5 and they are secured along the inner face of that upper edge of the pocket designated 6, which is stitched to the waistband, the button stitching passing into the waistband in the usual manner.

The closure portion 4 has button holes 7—7 to provide for closing the opposite ends of the pocket mouth and for projecting

the button heads to be engaged by the suspender hangers 8—8 in the usual way.

For closing the mouth of the pocket midway the button closures, an ordinary snap 5 head 9 is attached to the part 4 for engaging a snap socket on the opposing pocket edge 6 in the usual manner.

Fig. 5 illustrates a modified form of my 10 pocket, one that is specially intended for use on waistbands of trousers that have no suspender buttons.

In this form, the snap closures 10—10 are used in place of the button and button hole 15 closures, shown in Figs. 1, 2 and 3.

15 In either form of my pocket as described and shown, the end closures are spaced sufficiently inward from the ends of the pockets so that, when the pocket is closed, the end 20 closures constitute stops that prevent lifting the package of bills as a whole out of the pocket, thereby making it practically impossible for the wearer as well as a pick 25 pocket pulling out the contents of the pocket even if the middle closure should be open.

25 The buttons 5—5 serve a double function, that of the ordinary suspender button and in connection with the hangers 8—8 they 30 constitute the means for positively locking the mouth of the pocket so that the contents thereof cannot be surreptitiously removed.

Among other advantages in utilizing the end closures and the middle closure for the 35 pocket mouth is that the user, by opening the middle closure can readily slip off a bill from the pack within the pocket, as illustrated in Fig. 2, without disturbing the remaining ones of the pack of bills and without disconnecting any of the parts other than the central closure snaps.

40 When made of linen fabric, the inner portion of the pocket may have a chamois skin lining 12 to take up perspiration, see Fig. 5.

The structure of my safety pocket is such 45 that in applying it to new trousers, it adds practically no additional expense to the making of the trousers, it occupies practically no room and does not appreciably change the shape or form of the trousers waistband or render any portion thereof unusually conspicuous.

What I claim is:

1. In combination with the waistband of trousers and a pair of suspender buttons thereon; of a pocket sewn along one edge 55 of the mouth thereof to the waistband and over the suspender buttons, said pocket having button holes for the suspender buttons, whereby the pocket may be held closed by the suspender buttons.

60 2. In combination with the waistband of trousers, a pair of suspender buttons thereon and the suspender hangers adapted to engage the buttons; of a pocket sewn along one edge of the mouth thereof to the waistband 65 and over the suspender buttons, the said

pocket having button holes for the suspender buttons, whereby the pocket may be closed by the suspender buttons, and held from opening over the buttons by the suspender hangers.

70 3. In combination with the waist-band of a garment; of a fabric pouch having its opening extended the full length thereof, means for securing the pouch along the inside of the waist-band edge, a button attached to each end of that portion of the pouch attached to the waist-band, a button hole in each end of the outer or free portion of the pouch mouth that co-operates with the end buttons, and provision on the inner and 75 outer mouth edges of the pouch for closing the said pouch intermediate its ends.

4. In combination with the waistband of a garment, of a fabric pouch having its opening extending the full length thereof, means 80 for securing the pouch along the inside of the waistband edge, a fastener attached to each end of that portion of the pouch attached to the waistband and co-operating with the ends of the outer or free portion of 85 the pouch mouth to close the pouch mouth at the ends, and provisions for closing the pouch at a point intermediate its ends, the upper or waist edge of the pocket being opened between the places where the fastener 90 devices are located, whereby the contents of the pouch may be viewed, substantially as shown and described.

5. A safety pocket consisting of a flexible pouch detachable along one of the edges of 100 the opening or mouth thereof along the inside of a trousers waistband and over the pairs of suspender buttons on the inner face of the said band, the outer or free edges of the mouth portion of the pocket having button holes for closing over the suspender buttons, whereby connection of the suspender 105 straps with the said buttons effects closure of the mouth of the pocket at the opposite ends thereof.

6. A safety pocket consisting of a flexible pouch detachable along one of the edges of the opening or mouth thereof along the inside of a trousers waistband and over the pairs of suspender buttons on the inner face 110 of the said band, the outer or free edges of the mouth portion of the pocket having button holes for closing over the suspender buttons, whereby connection of the suspender straps with the said buttons effects closure 115 of the mouth of the pocket at the opposite ends thereof, and other means for closing the said mouth of the pocket at a point between the end closures.

7. In a safety pocket for carrying a flat- 120 wise assembled package of bills of currency, the combination with the waistband of trousers; of a pocket of a length and depth slightly greater than the length and width of the package of bills to be contained therein, 125 130

means for securing the open upper end of the pocket along the inner upper edge of the waistband of the trousers, the said open upper end having button-like closures, one at each end and which constitute stops that retard the lifting of the ends of the package of bills from the pocket and the said pocket also having a button closure midway the end

5

closures, the several closure devices operating to hold the package from being freely 10 bodily lifted out of the pocket and to permit of freely slipping out any single one of the bills when the intermediate closure has been opened.

JAMES C. DARST.
